UNITED STATES PATENT OFFICE.

WILLIAM H. ELKINS, OF CAMBRIDGE, MASSACHUSETTS.

DYNAMO.

SPECIFICATION forming part of Letters Patent No. 470,785, dated March 15, 1892.

Application filed July 11, 1891. Serial No. 399,235. (No model.)

To all whom it may concern:

Be it known that I, WILLIAM HENRY ELKINS, of Cambridge, in the county of Middlesex and State of Massachusetts, have invented 5 an Improvement in Dynamos, of which the following is a specification, reference being had to the accompanying drawing, which is a diagram illustrating my invention.

In my patent, No. 460,372, dated September 10 29, 1891, application filed November 28, 1890, I have described a dynamo the current in which is kept constant by dividing the circuit into two portions and carrying one of these portions through a part of the field-coil. My 15 present invention relates to dynamos constructed on the principle described in that patent; and it consists in a dynamo with two pairs of brushes, one brush of the positive pair connected to the positive terminal of a 20 circuit of which a portion of the field-coil and translating devices form a part, and the corresponding brush of the negative pair connected to the negative terminal of that circuit, the other brushes of the positive and 25 negative pairs being connected, respectively, to the positive and negative terminals through portions of the field-coil, which always carry less current than those portions of the field-coil which carry the same current as the translating devices, the number of turns of wire in 30 those portions of the field-coil with the smaller current being so proportioned to the number of turns of wire in the corresponding portions with the constant current as to produce equality of ampère-turns at full load, notwithstanding 35 the reduced current in the regulating portions of the coil and the constant current in the other portions of the coil.

B indicates the commutator; B', the armature, and D D' a positive and negative brush connected with the terminals T T' of the circuit which includes portions A A' of the field-coil and the translating devices. The other brushes D² D³ connect, respectively, with the 40 terminals T and T' through the coils A² and A³, and the number of turns of wire in these coils A² and A³ is such with relation to the number of turns in the coils A A' that while, say, ten ampères through coils A A' will give 45 a certain number of ampère-turns half that

number of ampères through coils A² A³ will give the same number of ampère-turns. These figures are taken for the reason that the brushes may be so adjusted that if ten ampères be assumed as the current desired in 55 the work-circuit five will flow through brushes D and D' and five through brushes D² and D³, making ten through the work-circuit and coils A A', but only five through coils A² A³. Hence coils A² A³, in this example of my invention, 60 will comprise twice as many turns as do the coils A A'; therefore the total number of ampère-turns which is suitable for full load.

On any decrease of resistance in the work-circuit (as by cutting out one or more lamps) 65 the current in that circuit would instantly increase were it not that the diameter of commutation shifts, thereby increasing the current through D and D' and decreasing the current through D² and D³ and also decreasing the number of ampère-turns energizing pole S. This so weakens the field that the total current remains nearly constant. Conversely, when the dynamo is running at a minimum load, any increase of resistance in 70 the work-circuit (as by introducing one or more lamps) would tend to instantly decrease the current in that circuit were it not that the diameter of commutation shifts in such a way as to decrease the current through D and 75 D' and increase the current through D² and D³, which increases the ampère-turns energizing pole S, and so strengthens the whole field as to keep the current substantially constant. 80

85 Of course an ammeter or its equivalent will be used in practice in the usual way, and proper appliances, either worked by hand or automatic, may also be used to more closely regulate the current; but these are matters so familiar to all skilled in the art that they need no description.

What I claim as my invention is—

In a constant-current dynamo, two pairs of brushes of like sign, as D D² and D' D³, one 90 brush of each pair, as D, connected to the corresponding brush of the other pair, as D', by a circuit of which portions A A' of the field-coils and translating devices form a part, the other two brushes of each pair, as D² and D³, 95 100

connected to the terminals T T' of that circuit through other portions A² A³ of the field-coils, the constant current at full load flowing through the main coils A A' and a smaller current flowing through the regulating-coils A² A³ and the number of turns of wire in the regulating-coils being materially greater than

the number of turns in the corresponding portions of the main coils, all substantially as described.

W. H. ELKINS.
